(74) Attorney, Agent, or Firm — James Ray and Assocs;
Alexander Pokot(57) **CLAIM**

The ornamental design for a pegboard adapter, as shown and described.

DESCRIPTION

The present application closely relates to co-pending U.S. nonprovisional patent application Ser. No. 15/336,039, titled “Pegboard Adapter and Method” and filed concurrently herewith by inventors Eshan Gupta and Anil Gupta.

FIG. 1 depicts a perspective view of one embodiment of a pegboard adapter showing my new design.

FIG. 2 depicts a front view of the pegboard adapter of FIG. 1.

FIG. 3 depicts a rear view of the pegboard adapter in FIG. 1.

FIG. 4 depicts a top view of the pegboard adapter in FIG. 1.

FIG. 5 depicts a bottom view of the pegboard adapter in FIG. 1; and,

FIG. 6 depicts a left side view of the pegboard adapter in FIG. 1. The right side view is identical.
